Primary Examiner — Susan Bennett Hattan(74) *Attorney, Agent, or Firm* — Fish & Richardson P.C.(57) **CLAIM**

The ornamental design for a container lid, substantially as shown and described.

DESCRIPTION

FIG. 1 is a perspective view of the container lid.

FIG. 2 is a back view of the container lid of FIG. 1.

FIG. 3 is a front view of the container lid of FIG. 1.

FIG. 4 is a side view of the container lid of FIG. 1.

FIG. 5 is an opposite side view of the container lid of FIG. 1.

FIG. 6 is a top view of the container lid of FIG. 1; and,

FIG. 7 is a bottom view of the container lid of FIG. 1.

The broken lines in the drawings depict environmental subject matter only and form no part of the claimed design.
